UNITED STATES PATENT OFFICE.

HANS MIKOREY, OF SCHÖNEBERG, NEAR BERLIN, GERMANY, ASSIGNOR
TO THE FIRM OF W. GRAAFF & COMPAGNIE GES. MIT BESCHR. HAFTUNG,
OF BERLIN, GERMANY.

HAND-OPERATED COLOR-SPRAYING DEVICE WITH INTERCHANGEABLE COLOR-RECEPTACLE.

No. 835,708.

Specification of Letters Patent.

Patented Nov. 13, 1908.

Application filed February 26, 1906. Serial No. 803,132.

To all whom it may concern:

Be it known that I, HANS MIKOREY, a civil engineer, and a subject of the German Emperor, and a resident of 13 Wartburgstrasse, in the city of Schöneberg, near Berlin, Kingdom of Prussia, and German Empire, have invented a certain new and useful Hand-Operated Color-Spraying Device with Interchangeable Color-Receptacle, of which the following is a specification.

This invention relates to a color-spraying or disintegrating device operated by hand and provided with interchangeable color-receptacle which is particularly distinguished by the fact that the receptacle for the dye or coloring-matter, together with automatically-closing discharge-nozzle, which is opened to my adjustable extent during the operation of the apparatus, is detachably and interchangeably arranged in relation to the supporting-frame of the spraying device. The said frame in its turn is so arranged and constructed that the receptacle-containing part of the device may be easily interchanged and besides being provided in connection with its handle with the means for admitting the compressed air serving for the operation of the disintegrator or sprayer it also possesses a controlling-lever detachably secured thereto and by means of which both the admission of the compressed air, as well as the discharge from the color-receptacle, may be regulated. The disintegration or spraying is produced by allowing the coloring-matter to pass from the receptacle and through the discharge-nozzle into a beak-shaped compressed-air nozzle, the color being thrown off as a spray by the compressed-air current.

The invention is intended to provide means for making it possible to interchange the color-receptacle with accessories in pieces of apparatus of this kind in such a manner that after the color-receptacle is detached the remaining of ports or passages filled with coloring-matter upon the frame of the apparatus is avoided, so that upon attaching another receptacle filled with a different coloring-matter the spraying operation can be immediately taken up again without it becoming necessary to provide first for the cleaning away of the remainders of color from the previous operation.

Upon the accompanying drawings a form

of construction of the spraying apparatus is shown, by way of example, in which—

Figure 1 is a side view of the apparatus, partly in section, while Fig. 2 is an end view of the supporting-frame with the receptacle removed.

The supporting-frame *a* is provided with feet *b*, a tubular part of which comprises the handle *c*, in the interior of which the valve-stem *p* is arranged, which serves for the actuation of the admission-valve *q* for the compressed air. The admission-conduit of the compressed air is secured at the lower end at *d*. Between the valve *q* and a stuffing-box *e*, situated in the interior of *c*, the compressed-air pipe with the beak-shaped nozzle *z* is branched off, the said compressed-air pipe being downwardly inclined. The valve-stem *p* is pressed upward by a spring *f*, corresponding to the normal position of the valve *q*.

h in the construction illustrated in the drawings indicates a lever for the operation of the valve and detachably secured to the rotating pivot *i*, while the front end of the said lever is forked at *g*. The part facing said fork-shaped part is plate-shaped. The lever may be depressed by the thumb of the hand with which the operator takes hold of the apparatus at the handle *c*, and upon depressing the said lever the valve-rod *p* is actuated, so as to be able to control the opening of the valve *q*. In order to be able to detach the lever *h* from the stud or pivot *i*, the lever is provided with a spring *j*.

The detachable color-receptacle is indicated at *r*. It is detachably secured to the supporting-frame, which is effected by the engagement of hooks *n* with recesses of flanges *a'*, provided in the upper part of the frame and, on the other hand, by inserting the cylindrical base *o* of the receptacle in a socket *a²* of the said frame. The said socket is in the shape of a sleeve open at the front, and a bayonet-lock ring *x*, with projection *y*, allows to lock the parts in their respective positions after having inserted the ring at the open side of the socket and turning the projection *y* so as to engage below *a²*.

The base part *o* of the receptacle is provided at its lower end with a discharge-nozzle *w*, from which the coloring-matter when the receptacle is in the position shown in Fig.

1 of the drawings may flow down directly upon the beak-shaped compressed-air nozzle *z*. The discharge from said nozzle is normally closed, and it is controlled during the 5 operation of the apparatus by a valve *v*, with valve-rod *u*, which extends upward in the interior of the tubular rear part of the receptacle *r* and which projects at the upper end through the part *g* of the lever *h*. Upon the 10 insertion of the receptacle *r* in the supporting-frame the lever *h* may be temporarily removed, if necessary, to be fixed up thereafter again in operative position.

By means of a spring *s* the rod *u* of the 15 valve *v* is forced downward in such a manner that the valve *v* will keep the discharge-opening for the coloring-matter normally closed. The end of the rod *u* which is situated above *g* is provided with an adjustable stop or button *k*, so that upon depressing the lever *h* at the far-off end the valve-rod *u* is raised and the valve *v* opened, beginning with a certain 20 length of stroke of the rod. The arrangement is such that when the lever *h* is operated the admission-valve *g* for the compressed air is first opened and only then the valve *v* is 25 opened, so as to be able to adjust the area of said opening. The adjustability is effected by providing the button *k*. The jet of compressed air issuing from a slot and passing 30 along the spoon-shaped face of the nozzle *z* meets the jet of coloring-matter issuing from the nozzle *w* and disintegrates the same, the sprayed or disintegrated color being carried 35 away in a downwardly-inclined direction. The arrangement and the position of the nozzles *w* and *z* in the base part of the frame *a* makes it possible to direct the sprayed jet into immediate proximity of the surface 40 which is to be covered with the coloring-matter.

When it is desired to exchange the color-receptacle for another, it is only necessary to turn the bayonet-ring *x* somewhat in such a 45 manner that the projection *y* is placed in front at the open part of the socket *a²*. The receptacle may then be lifted off easily by

disengaging the hooks *n* from the frame. If necessary, the lever *h*, which is only retained in position on its pivot *i* by the flat spring *j*, 50 should be previously removed. When another color-receptacle is inserted into the apparatus in place of the former receptacle, it is not necessary any more with the device hereinbefore described to take into account 55 the inconveniences prevailing in the spraying and dispersing apparatuses, as hereinbefore employed, where communicating passages and other parts of the apparatus remain filled and clogged up with the coloring-matter of 60 the former receptacle and had to be cleaned out first.

The arrangement and construction according to this invention, in which the detachable color-receptacle is itself provided with the 65 discharge-nozzle and with the corresponding discharge-regulating device, allows of effecting the replacement of the receptacles at once, the new receptacles being then in condition for immediate operation. After the receptacle is detached it is automatically closed.

What I claim, and desire to secure by Letters Patent of the United States, is—

Hand-operated color dispersing or spraying apparatus with compressed-air admission, 70 comprising a supporting-frame, a handle on said supporting-frame, compressed-air-admission conduit, compressed-air nozzle and regulating-lever all mounted on said frame, any color-receptacle being detachably and 75 interchangeably connected to said supporting-frame, a discharge-nozzle and shutting and controlling devices for the said nozzle being provided on said receptacle and co-operating with the regulating-lever, the said 80 discharge-nozzle being fitted over the compressed-air nozzle.

In witness whereof I have hereunto signed my name this 9th day of December, 1905, in the presence of two subscribing witnesses.

HANS MIKOREY.
